UNITED STATES PATENT OFFICE.

OTTO WINKLER, OF CÖPENICK, GERMANY, ASSIGNOR TO GENERAL ELECTRIC COMPANY, A CORPORATION OF NEW YORK.

SELF-LEVELING CARBURETER.

1,118,459.

specification of Letters Patent. Patented Nov. 24, 1914.

Application filed September 4, 1912. Serial No. 718,491.

To all whom it may concern:

Be it known that I, OTTO WINKLER, a subject of the King of Prussia, residing at Cöpenick, Germany, have invented certain 5 new and useful Improvements in Self-Lev-eling Carbureters, of which the following is a specification.

This invention relates to charge-forming devices for internal combustion engines, and 10 has especial reference to the engines used to drive aeroplanes. When a float-controlled carbureter is employed in an engine-propelled flying machine, difficulties have arisen from the inclined positions assumed 15 by the machine, which not only prevent the free movement of the float but also bring the level of the gasoline too far below or above the nozzle opening to permit proper vaporizing. In consequence of this, the composition of the mixture is unfavorably affected.

My invention is intended to remedy these troubles and to this end it comprises means for mounting the float chamber and nozzle 25 in such a manner that they will be self-leveling, oscillating freely in all directions about a point which preferably coincides with the mouth of the nozzle.

In the accompanying drawing, Figure 1 30 is a sectional elevation of a float carbureter embodying my invention, and Fig. 2 is a sectional plan view of the same on the line 2—2, Fig. 1.

The intake pipe 1 of the engine is sta- 35 tionary with respect to said engine, and is provided with the customary throttle valve 2 for the mixture. The open end of said pipe through which air is drawn is a bell-shaped funnel 3. The nozzle 4 of the carbureter is located inside of this funnel, and 40 is connected by the pipe 5 with the float chamber 6.

The chamber and nozzle are not rigidly connected to the intake pipe, but are car- 45 danically suspended thereon, on axes intersecting at right angles at the mouth 7 of the nozzle 4. For example, the chamber 6 and an arm 8 extending from the pipe 5 are pivoted on trunnions 9 at diametrically op- 50 posite points on a ring 10 which lies in the plane of the mouth of the nozzle and in turn is mounted on pivots 11 lying in the same

plane at right angles to the trunnions 9 and supported in bearings 12 on the intake funnel 3. This construction forms the well 55 known gimbal bearing for mounting mariners' compasses.

To insure a constantly level position for the carbureter, a weight 13 is hung on a rigid arm 14 extending downwardly from 60 the nozzle, and operates like a pendulum to correct any tendency of the carbureter to tilt. The gasoline is fed to the float chamber through a flexible tube 15.

In accordance with the provisions of the 65 patent statutes, I have described the principle of operation of my invention, together with the apparatus which I now consider to represent the best embodiment thereof; but I desire to have it understood that the 70 apparatus shown is only illustrative, and that the invention can be carried out by other means.

What I claim is new and desire to secure by Letters Patent of the United States, is: 75

1. The combination in a carbureter of a stationary intake pipe, a float chamber, a nozzle connected therewith, and means for suspending the float chamber and nozzle with relation to the intake pipe which permits them to automatically maintain a level position when the carbureter is tilted.

2. The combination in a carbureter of a stationary intake pipe, a float chamber, a nozzle connected therewith, and means car- 80 danically suspending the float chamber and nozzle on axes intersecting said nozzle.

3. A carbureter having its float chamber and nozzle mounted on gimbals in the plane of the mouth of the nozzle.

4. The combination in a carbureter of a stationary intake pipe, and a float chamber and nozzle mounted on gimbals supported on said pipe.

5. A carbureter having its float chamber and nozzle carbanically suspended on the air intake pipe, and a rigid weighted arm depending below said float chamber.

In witness whereof I have hereunto set my hand this 20th day of August, 1912.

OTTO WINKLER.
